WALL-MOUNTED TRANSFORMER FOR DIAGNOSTIC INSTRUMENTS

Lew F. Allyn, Skaneateles, N.Y., assignor to Welch
Allyn, Inc., Skaneateles Falls, N.Y., a corporation
of New York

Filed May 9, 1968, Ser. No. 11,875

Term of patent 14 years

Int. Cl. D13—02; D24—02
U.S. Cl. D26—15

FIG. 1 is a front perspective view as seen from the upper left front of a wall-mounted transformer for diagnostic instruments embodying my new design;

FIG. 2 is a rear perspective view as seen from the upper left rear thereof; and

FIG. 3 is a bottom plan view thereof.

The broken lines are shown for illustrative purposes only.

I claim:

The ornamental design for a wall-mounted transformer for diagnostic instruments, substantially as shown and described.
